CLAIM

The ornamental design for a multifunctional storage bag for CD player, as shown and described.

DESCRIPTION

FIG. 1 is a front perspective view of a multifunctional storage bag for CD player, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is a front view showing the multifunctional storage bag for CD player in an open state; and,
FIG. 10 is a rear view showing the multifunctional storage bag for CD player in an open state.

The broken lines in the drawings illustrate the portions of the multifunctional storage bag for CD player, which form no part of the claimed design.
